ERNEST L. SMITH, OF SAN FRANCISCO, CALIFORNIA, ASSIGNOR, BY MESNE
ASSIGNMENTS, TO LUIS J. MARCUS AND JOHN A. LESOINE

APPARATUS FOR CURLING HAIR

Application filed May 20, 1929. Serial No. 364,409.

This invention relates to improvements in hair curling apparatus, and more particularly that type set forth in my co-pending applications Serial Numbers 286,809; 344,256 and 352,026, filed respectively June 20th, 1928; March 5th, 1929 and April 2nd, 1929.

It has been discovered in the use of hair clamping means together with a hair winding spindle, which during the curling operation is heated, with the hair wound thereon, that it is essential to protect the scalp from the steam generated during the heating of the moistened hair. It is to accomplish this result that the present apparatus is designed.

Among its objects, the present apparatus has to provide a hair gripping means longitudinally of which a curling spindle is operatively mounted and positioned. A further object is to provide a structure wherein a bar or rod of simple construction may be employed in connection with the usual supporting block, thereby reducing the cost of the hair gripping mechanism. A further object is to provide a novel form of elastic gripping means which is capable of being cheaply constructed and extremely efficient for the purpose designed.

Broadly, the invention consists in grooving the side edge of a gripping block and pivotally associating therewith a gripping bar mounting a yieldable surface between which and the block the hair is securely gripped prior to the winding of the free end of the hair on the spindle, and in providing a structure wherein steam generated in the curling operation may escape readily from the curling apparatus.

With the above mentioned and other objects in view, the invention consists in the novel construction and combination of parts hereinafter described, illustrated in the accompanying drawing and pointed out in the claims hereto appended; it being understood that various changes in the form, proportion, size and minor details of construction within the scope of the claims may be resorted to without departing from the spirit or sacrificing any of the advantages of the invention.

To more clearly comprehend the invention, reference is directed to the accompanying drawing, wherein—

Figure 1 is a view in elevation of the preferred embodiment of my invention, with the parts in closed position.

Figure 2 is a similar view, with the clamping rod in open position.

Figure 3 is a view in end elevation of the gripping part with one of my improved spindles mounted thereon.

Figure 4 is a sectional view through the structure illustrated in Figure 3, with a lock of hair raised from the scalp and gripped, and with its free end wound around the spindle.

Figure 5 is a view in perspective of a slotted protecting pad through which the lock of hair is extended.

Referring more particularly to the drawing, wherein like characters of reference 70 designate corresponding parts, 1 indicates a gripping block, preferably of bakelite or other suitable material, the block being elongated in plan and having a longitudinal groove or depression 2 extending the full length of its upper surface. The block is also formed on one edge with a longitudinal groove or depression 3 in which is adapted for reception a gripping bar 4 fulcrumed at one end, as at 5', to a member secured to the block. 80 The bar 4 is of a length co-extensive with that of the block 1, and at its free end pivotally mounts a link 5, which, in turn, on its end mounts a cam lever 6 adapted for pivotal movement to engage in a cam seat 7 formed in 85 the rear wall of the block 1 near one end.

Between its fulcrum point 5' and the point of attachment of the link 5 thereto, the gripping bar 4 mounts a tubular member 8, preferably of elastic material, and of a diameter 90 greater than that of the bar 4, as illustrated in Figure 4 the elasticity permitting said member 8 to be distorted.

Upwardly from the opposite ends of the longitudinal depression 2 on the upper surface 95 of the block 1 project the spring pawls 9 for engaging the opposite ratchet ends 10 of my well known hair winding spindle 11, fully illustrated and described in the aforementioned pending applications.

The pawls 9 hold the spindle 11 in its wound position, as hereinafter described, and the spindle contains the usual electric heating elements or resistance coil 12.

In operation—a lock of hair 13, of the desired size, is lifted from the scalp 14 and separated from the remaining hair, and is passed through the longitudinal knife-slot 15 as shown in Fig. 5, in the elongated protecting pad 16, of any suitable structure, such 110

as felt. The gripping bar is moved to open position and the block 1 is moved into contact with the pad 16, with the lock of hair extending through the slot 15, lying parallel with the grooved edge of the block 1. The gripping bar 4 is then moved to closed position, tightly compressing the portion of the hair lock immediately above the pad 16 into the groove 3, and the pressure is such as to distort the material of the tubular member 8, as clearly illustrated in Fig. 4.

It will thus be apparent that the lock of hair extends upwardly from the gripping block 1, at one longitudinal side edge. The free end of the lock is wrapped about the spindle 11 and as the spindle is rotated, winding the hair thereon, the same is moved to a position longitudinally of the groove 2, immediately above the gripping block 1.

20 The ratchets 10 are gripped beneath the pawls 9, and as the spindle is further rotated, it will be observed that the hair lock is tightly wrapped therearound and the portion above the gripping bar 4 and block 1 is drawn taut. When in this position, the shield or hood 17 is positioned over the spindle and the electricity is supplied to the element 12. The shield or hood 17 does not completely encircle the spindle with the hair wrapped thereon, but has a free end adjacent the distortable member 8, as shown in Fig. 4. This heating operation which forms the curl, causes a steaming of the hair lock which has been previously moistened, but due to the presence of the protecting pad and the location of the gripping bar 4, at one side of the block, the steam is not forced or permitted to pass downwardly into contact with the scalp but escapes between the distortable member 8 and the edge of the hood adjacent thereto. Thus any liability of the head of the patient becoming burned is removed.

I claim:—

45 1. A hair curling apparatus comprising a unitary gripping block, a gripping bar operatively associated with one side edge thereof and extending longitudinally thereof and between which and the side edge of the gripping block a lock of hair is releasably gripped, a winding spindle disposed longitudinally of the upper surface of the gripping block between its side edges, and a hood in spaced parallel relation to the winding spindle and adapted to grip the hair around the spindle, said hood having one edge forming a seal with the gripping block and a free edge spaced from the gripping block providing an elongated opening for escape of steam and heat generated within the hood.

50 2. A hair curling apparatus comprising a unitary gripping block longitudinally

grooved on one side edge, a gripping bar pivotally mounted at one end and for reception within the longitudinal groove at the side edge of the gripping block and between which and the gripping block a lock of hair is releasably clamped, a spindle around which the free end of the gripped lock is wound, said spindle extending longitudinally of the block between its side edges, and a hood in spaced parallel relation to the winding spindle and adapted to grip the hair around the spindle, said hood having one edge forming a seal with the gripping block and a free edge spaced from the gripping block providing an elongated opening for escape of steam and heat generated within the hood.

55 3. A hair curling apparatus comprising an elongated unitary gripping block formed on one longitudinal side edge with a groove, a spindle detachably mounted longitudinally and centrally of the gripping block and adapted for winding the free end of a hair lock, means offset in a vertical plane from the longitudinal axis of the spindle for clamping the hair lock at its base within the groove in said gripping block and a hood mountable over the spindle in a manner to permit steam formed under the hood in the hair curling operation to escape between the said clamping means and the adjacent edge 60 of the hood.

4. A hair curling apparatus comprising the combination of a means for gripping a lock of hair extended upwardly from the scalp, a spindle thereon for forming the free end of the gripped hair in a curl, a hood mounted over said spindle, an electric coil within the spindle, and a protecting pad slotted between its ends and positioned below the gripping means and upwardly 65 through which the hair lock extends.

5. A hair curling apparatus comprising a longitudinal mounting block of unitary structure, a spindle mounted longitudinally and centrally of said block and adapted to receive a lock of hair, a hood adapted to positioning over said spindle with one of its side edges spaced adjacent said mounting block providing an elongated opening between the mounting block and the adjacent edge of the hood, a gripping bar operatively associated with one side of the mounting block, said gripping bar being positioned and arranged so that steam created under the hood by the hair curling process may escape between the gripping bar and the adjacent edge of the hood.

In testimony whereof I have signed my name to this specification.

ERNEST L. SMITH. 125
